UNITED STATES PATENT OFFICE.

THOMAS J. MITCHELL AND JAMES A. McCREARY, OF UNIONTOWN, PENNSYLVANIA.

COKE-OVEN APPARATUS.

No. 891,850.

Specification of Letters Patent.

Patented June 30, 1908.

Application filed January 30, 1908. Serial No. 413,484.

To all whom it may concern:

Be it known that we, THOMAS J. MITCHELL and JAMES A. McCREARY, citizens of the United States, residing at Uniontown, in the 5 county of Fayette, State of Pennsylvania, have invented a new and useful Coke-Oven Apparatus, of which the following is a specification.

This invention has reference to improvements in means or apparatus for use in connection with coke ovens, and its object is to provide a means for the removal of the coked material from the oven after the coking operation has been completed.

15 The invention comprises a suitable track carrying means whereby the truck is made self moving and the same prime mover which imparts motion to the truck is utilized for the purpose of operating the ram or pushing apparatus by means of which the coke is 20 pushed as a body out of the coking oven.

The invention also comprises a telescopic structure, one member of which carries a pushing head and mechanism whereby the 25 several telescopic members, which are projected in regular order, are coupled together for unit movement and are then withdrawn and uncoupled in the reverse order.

The invention will be best understood on 30 reference to the following detailed description, taken in connection with the accompanying drawings forming a part of this specification, in which drawings—

Figure 1 is a plan view of the truck and 35 pushing mechanism or ram carried thereby, said ram being in the retracted position. Fig. 2 is an end elevation of the structure shown in Fig. 1. Fig. 3 is a longitudinal section on a larger scale than shown in Figs. 1 and 2, of the telescoping members at a point coincident with the latch. Fig. 4 is a similar 40 section to that shown in Fig. 3, but with certain of the telescopic members in a different phase of operation. Figs. 5 and 6 are perspective views of details of the latch mechanism. Fig. 7 is a cross section of the telescoping members at the point adjacent to the propelling pinion, and Fig. 8 is a bottom plan view of the rack bars.

45 Similar numerals of reference are employed to indicate corresponding parts throughout the several figures of the drawings.

Referring to the drawings, there is shown 50 in Figs. 1 and 2, a rectangular frame 1, which may be made of I-beams, suitably riveted

together, and this frame is mounted upon axles 2 through the intermediary of suitable journal boxes 3. Upon the axles between the journal boxes, are mounted truck wheels 4—5, the wheel 4 being provided with flanges on each side to embrace a track rail 6, while the wheel 5 may have a flange on the inner face only.

The track rails 6 are usually laid between 65 two series of coke ovens which, in Fig. 2, are indicated conventionally at 7 and 8, and the framework 1 overhangs the track for the purpose of providing a broad support for the several parts carried thereby.

70 Mounted upon the truck near one corner thereof is an electric motor 9 which may be of any suitable type and receives current from a suitable trolley wire, not shown, through a trolley pole 10 of any suitable construction.

75 The armature shaft 11 of the motor carries a pinion 12, meshing with a gear wheel 13 upon another shaft 14 extending lengthwise of the truck, and is supported thereon 80 by suitable journal boxes 15. At the end remote from the motor 9, the shaft 14 carries two pinions 16 and 17, spaced one from the other. The pinion 16 is considerably smaller than the pinion 17 for a purpose which will 85 presently appear. The pinion 16 is in mesh with a gear wheel 18 upon a counter-shaft 19 below and to one side of the shaft 14, and suitably mounted in journal bearings 20 in the truck frame. The gear wheel 18 is loosely 90 mounted upon the shaft 19 and may be coupled thereto at will by means of a clutch 21 under the control of a suitable handle 22. This clutch is not shown in detail, but is only conventionally indicated since it may be of 95 any suitable type. The pinion 17 is in mesh with another pinion 23 upon the shaft 19, but is loosely mounted thereon to be coupled thereto through another clutch 24 like the clutch 21, and, also, under the control of the 100 handle 22.

The frame 1 has intermediate cross girders 25 serving as a support for certain structures which will be hereinafter referred to. The shaft 19 extends entirely across the space 105 occupied by the girders 25, and beyond the same at the end remote from that carrying the gear wheel 18 and pinion 23 is another pinion 26 in mesh with a gear wheel 27 upon a counter-shaft 28 having journal bearings 29 110 on the girders 25, and this shaft 28 extends across the space occupied by the girders 25;

and at the end remote from the gear wheel 27 carries a pinion 30 which in turn is in mesh with a gear wheel 31 on the shaft 32, having journal bearings 33 on the girders 25, and between these girders the shaft 32 carries a wide pinion 34, the purpose of which will presently appear.

Adjacent to the shaft 14 on the side thereof remote from the shaft 19 is another counter-shaft 35, carrying a gear wheel 36, in mesh with the pinion 16 before referred to. The shaft 35 is suitably journaled on the framework of the truck, as indicated at 37. The gear wheel 36 is not fast upon the shaft 35, but is coupled thereto by means of a clutch 37' under the control of a handle 38 located within convenient distance of the clutch handle 22, and connected to the clutch 37' through bell crank levers 39 and a connecting link 40.

The shaft 35 has fast thereon, a bevel pinion 41 engaging another bevel pinion 42 upon an upright shaft 43, and this last named shaft carries still another bevel pinion, not shown, in mesh with still another bevel pinion 44 upon a short counter-shaft 45, the latter carrying a straight pinion 46 meshing with a gear wheel 47 upon corresponding axle 2.

Now, let it be assumed that the motor 9 has started, say through the intermediary of a controller 48', located adjacent to the operating lever 22 and handle 38, then motion is imparted by said motor to the shaft 14, and to the pinions 16 and 17. This motion is, also, transmitted to the gear wheels 18, 23 and 36, but assuming that the clutches are not in operative position, these gear wheels simply rotate idly. Now, if the clutch 37' be put in operative position, then motion is transmitted from the pinion 16 and gear wheel 36 to the shaft 35 and through the bevel gear to the pinion 46, and ultimately to the gear wheel 47 and the axle 2. The truck is thereby propelled along the track 6 at a speed depending upon the initial speed of the motor 9 and the reduction of speed through the train of gears. This will drive the truck in a certain direction along the track, and if it is desired to reverse the direction of travel of

the truck, then the direction of rotation of the armature of the motor 9 is reversed. The rate of reduction between the motor and the car wheels is such that the truck is moved at a very moderate speed, while the motor runs at a comparatively high speed, which latter is necessary for the economical running of the motor.

When it is desired to impart rotative movement to the pinion 34 for purposes which will hereinafter appear, then the clutch 21 is put into active operation, thus coupling the gear wheel 18 to the shaft 19. Now, however, the motion of the shaft 14 is transmitted at a progressive reduction of speed through the shaft 19, pinion 26, gear

wheel 27, shaft 28, pinion 30 and gear wheel 31, so that the speed of the shaft 32 carrying the pinion 34 is comparatively slow since the parts to be moved are ponderous and large power with slow movement is permissible.

Assuming that the movement imparted to the pinion 34 was such as to cause the forward or operative movement of the parts controlled by said pinion, and that in this forward movement the work is to be performed while the return movement is to transpire without load, then the return movement may be more rapid than the forward movement for far less power is required. For this purpose, the direction of rotation of the motor armature is reversed and the gear wheel 23 is clutched to the shaft 19. The gear 17 may for this purpose be made as large as or larger than the gear wheel 23, and considerably larger than the pinion 16, so that the return movement may be more rapid than the forward movement.

Mounted upon the frame 1 in line with, and above the girders 25, are two spaced channel beams 48, connected at their tops by a cap plate 49. These channel beams are somewhat longer than the distance between the sides of the truck and project over one of the side members for a short distance, and the cap plate 49 is as long as the channel beams.

Carried on the inner faces of each channel beam 48 are a number of flanged rollers 50, each carried by a short axle 51, and spaced from the channel beam by a washer 52. The axle extends through the channel beam and is there threaded, as indicated at 53, to receive a nut 54, there being a washer 55 interposed between the nut and the outer face of the corresponding channel beam. There are as many of these rollers as are necessary, and carried by them is a member 56 of telescoping structure, this member being made up of sides composed of channel beams 57 having their flanges embracing the peripheries of the rollers 50, and supported by the engagement of these rollers with the upper flange of the channel beams, and the said channel beams are connected by a top plate 58. The channel beams 57 are provided with rollers 59 mounted in the channel beams 57, like the rollers 50 in the channel beams 48.

Supported by the rollers 59 is a second member 60 of the telescoping structure, and this member has sides formed of I-beams 61 connected by a cap plate 62, but the I-beams carry no rollers. The outer flanges of the I-beams embrace the rollers 59 and are supported thereby; and the inner flanges of the I-beams receive similar rollers 63 journaled on axles 64, like the axles 51, and these said axles are carried by two spaced channel beams 65 connected at the top by a plate 66 and at the bottom by another plate 67. There is thus formed a telescoping structure

composed of three members, each supported on the next outer one by roller bearings, and the outermost one being supported by roller bearings in a fixed housing composed of the 5 channel beams 48 and cap plate 49.

The members of the telescoping structure are of sufficient length so that when retracted they are all substantially contained within the fixed housing, and when projected they 10 have a sufficient length to more than extend through a coke oven with which the structure is designed to operate.

The plate 67 is formed on its lower face with gear teeth 68 to constitute a longitudinal rack. Fast to each I-beam 61 is a 15 rack bar 69 flanking the rack 68 and extending longitudinally with relation to said I-beams. On the lower edge of each channel beam 57 there is another rack bar 70 20 flanking the rack bars 69 immediately adjacent thereto.

When the several members of the telescopic structure are in the retracted position only the central member has the rack bar in 25 engagement with the teeth of the pinion 34, and the structure is such, as will presently appear, that when the central member has been projected by the pinion until in a position about to escape from said pinion, the 30 next outer member is coupled to the first member and is moved by the same into engagement with the pinion, and is itself projected, carrying the first named member with it, and when the second named member 35 has about reached the outer limit of its travel under the direct impulse of the pinion, then the third member is coupled to the second member and brought into mesh with the pinion to be in turn projected by the pinion 40 after the second member has escaped from the latter. Thus there is a progressive outward movement of the several members of the telescoping structure, and when the parts are reversed the retraction takes place in like 45 manner, but in reverse order.

Near that end of the housing for the telescoping structure from which the telescoping members are projected, is secured a bracket 71 fast on the top plate 49, and this 50 bracket is immediately above an opening 72 in said top plate. The bracket 71 carries and guides a stem 73 terminating in a latch head 74 of rectangular shape projecting downwardly through the opening 72 and 55 normally through other openings 75 and 76 in the respective top plates 58 and 62 of the outer and intermediate telescopic members. The lower face of the head 74 is beveled, as indicated at 77, in a direction toward the 60 rear end of the telescopic members, and a helical spring 78 surrounds the stem 73 between the head 74 and the top of the bracket 71, and tends normally to urge the head 74 toward the telescopic members. The openings 65 75 and 76 are near the front ends of the re-

spective telescopic members, and the front edge of each opening is reinforced by plates 79 fast on both the top and bottom faces of the top plates 58 and 62. When the head 74 is in position to be projected through the 70 openings 75 and 76, however, downward movement is prevented by a shoulder coming in contact with the top plate 49.

Secured to the under side of the top plate 66 of the innermost telescopic member at its 75 rear end is a strong bracket 80 having a through perforation in which is seated a rectangular pin 81, the upper end of which latter normally engages the under side of the top plate 62 of the intermediate telescopic 80 member, and one edge of this pin, at its upper end, is slightly rounded, as indicated. Near the lower end of the pin 81 is formed a flange 82, which, by engagement with the lower end of the bracket 80, serves to limit 85 the upward movement of the said pin 81. Below the flange 82 the pin is reduced in diameter to form a tongue 83 through which there is a perforation 84 for the passage of a pin 85. The tongue 83 is seated between 90 two spaced parallel ears 86 on one end of a rock lever 87, and these ears have elongated perforations 88 for the pin 85. The rock lever 87 has formed on it, near its upper edge, about mid-way of its length, two laterally 95 oppositely extending bosses 89 of such length as to reach the side beams 65 of the innermost telescopic member, and the lever is secured to these side beams by a pin 90. Cotter pins 91 are used to maintain the pin 85 in 100 place, and similar means may be used for maintaining the pin 90 in place.

The end of the lever 87 remote from the ears 88 is formed with a ledge 92, from which there projects upwardly a stud 93, receiving 105 the lower end of a helical spring 94, the upper end of which is received on another stud 95 on a bracket 96 secured to the inner telescopic member. Formed on the stud 95 there is a pin 97 extending through the 110 spring 94 into the path of the stud 93, and this pin serves to limit the movement of the lever 87 about the pivot pin 90 in a direction to bring the stud 93 toward the stud 95. The action of the spring 94, however, is to 115 force the lever 87 about its pivot in a direction to move the stud 93 away from the stud 95, and thereby cause the pin 81 to move upwardly through the bracket 80. Normally the upward movement of the pin 81 is arrested by engagement with the under side of 120 the plate 62. The intermediate telescopic member is, also, provided near its rear end with a similar structure to that just described, and it is unnecessary to repeat this 125 description, since the parts are identical, except that the pin corresponding to the pin 81 is somewhat longer and for the convenience of the following description, this pin is designated by the reference numeral 98, in order 130

that this pin may be differentiated from the pin 81, and the lever controlling this pin is designated by the numeral 99 for the same reason, although it is in all respects identical 5 with the lever 87.

The innermost telescopic member carries at its front end beyond the housing, a pushing or ram head 100, which is extended laterally to about conform to the width of a coke 10 oven door, and to prevent injury to the floor and side walls of the oven, the head is provided with curved plates 101, on the under edge, and, also, on the sides, these plates acting both as wearing plates and preventing 15 the edges of the head or ram from catching in projections or irregularities of the floor or side walls of the oven, and so causing injury.

On the rear end of the housing of the telescoping members is a buffer head 102 formed 20 on a body portion 103 capable of movement and adjustment between two guides 104 fast on the top plate 49. This buffer is so located as to be readily made to engage the walls of the series of ovens 8 when the ram or pushing head 100 is being moved into the ovens of the series 7.

Now, let it be assumed that the parts are in the position shown in Fig. 3, that is, the innermost telescopic member is being projected and the inner end is approaching the pinion 34. Ultimately the pin 81 engages the beveled face 77 of the pin 74 and raises the same against the action of the spring 78 sufficiently to unlock the second section and thereby allow it to be moved forward, the beveled face 77 by this outward movement entirely freeing the pin 74 from its slot 76. When the intermediate section is released by this raising of the bolt 74, the pin or bolt 81 40 comes in contact with the reinforcement 79 on the under side of the next outer section and moves the outer section forward until the rack 69 comes in gear with the pinion 34, and at the same time the rocking lever 87 45 comes in contact with the periphery of the pinion 34 and thereby forces the pin 81 through the opening 76 by which means the two sections are firmly locked together, the spring 94 holding this bolt 81 in place when 50 forced there by the action of the rocking lever 87. Now, the inner telescopic member and the intermediate telescopic member are coupled together and as soon as this has been done, the pinion leaves the teeth 68 and both 55 members are projected by the engagement of the pinion with the rack bars 69. The lever 87 in this position has the end under the control of the spring 94 now forced down through the slot 105 to a distance about equal to the 60 depth of the teeth 68. The second section is provided with a locking device similarly located near the rear end similar to the first one and arranged to operate in the same manner. As it approaches and comes into 65 contact with the pinion 34, locking this sec-

ond section firmly to the next outer or third section then all three sections are forced outward by the pinion 34 and rack 70 of the third section, the operation of locking the sections together being identically similar in 70 each case.

The forward or outward movement of the ram or pushing head has caused the latter to enter a coke oven opening, and to push the coked charge out through the other end of the oven, which latter is of a type permitting 75 this operation, and the mass of coked material is pushed out as a whole, thus preserving it in large sections. On reversing the mechanism, the outermost section is retracted until ultimately the head 74 is coincident with the opening now occupied by the pin 98, and when this position is reached, the pinion 34 engages that end of the lever 99 directly under the spring 94 and forces the 80 same upward against the action of said spring, thus drawing the pin 98 out of the opening 75 and permitting the head 74 to drop into said opening under the action of the spring 78, until this head engages the 85 upper face of the plate 62. This action takes place practically coincident with the passing of the rack bars 70 from engagement with the pinion 34, or more properly, immediately after, and the beveled face 77 of the 90 head 74 will then ride down the rear edge of the opening 75 and ultimately seat itself as described, and thus lock the outermost telescoping member from further retractive movement. Now, the rack bars 69 of the 95 intermediate member have by this time come into engagement with the pinion 34, and the retractive movement of the intermediate member is continued until the pin 81 is brought into coincidence with the head 74, 100 and this pin is withdrawn by the engagement of the pinion 34 with that portion of the lever 87 then in the path of the pinion 34 in the manner before described with reference to the lever 99, and so the intermediate section 105 is locked against further retractive movement just after the rack bars 69 have escaped from the pinions 34. The innermost member, however, has its teeth 68 in engagement 110 with the pinion 34, and its retractive movement continues until the innermost member is housed to the extent desired, when the clutch 24 which, as before described, is used for the retractive movement, is disengaged, or the motor 9 is stopped. Should there, 115 however, be a lack of strict coördination of the parts, due to wear or the want of good fit, or from some other cause, the rounded edges of the pins 81 and 98 will cause these pins to ride under the respective plates 120 through which they project after either one of the pins has been sufficiently retracted to bring the rounded edge into engagement with the rear wall of the respective openings 75 or 76.

The ram or pushing head 100 is located some little distance above the tracks, and there is, therefore, a tendency to lift the truck from off the tracks when the coked charge is being pushed out of the oven. To avoid this, the frame 1 is provided near each end, with a downwardly extending bracket 106, in which is journaled a roller 107 having a flange 108. This roller 107 is journaled on 5 a vertical axis, so that it lies horizontally, and is so arranged that the tread of the roller bears against the side of the crown of the rail with the flange 108 engaging underneath said rail crown. Any tendency of this end 10 of the truck to rise over the tracks is thus resisted by the flanged roller 107.

We claim:—

1. In a coke oven apparatus, telescoping members adapted to be projected into a coke oven, a latch member carried upon a fixed portion of the structure in operative relation to one of the telescoping members, and a locking member carried by another telescoping member and arranged to engage and 20 move the latch out of engagement with the first named telescoping member and at the same time lock the second named telescoping member to the first named member.

2. In a coke oven apparatus, telescoping members adapted to be projected into a coke oven, a spring actuated latch member carried upon a fixed portion of the structure in operative relation to one or more of the telescoping members, and a locking member carried by another telescoping member and arranged to engage and move the latch out of engagement with the first named telescoping member, and at the same time lock the second named telescoping member to the first 35 named member.

3. In a coke oven apparatus, telescoping members adapted to be projected into a coke oven, a spring actuated latch member carried upon a fixed portion of the structure in operative relation to one or more of the telescoping members, and a locking member carried by another telescoping member and arranged to engage the latch member, said locking member being actuated by a lever 50 and arranged to move the latch member out of engagement with the first named telescoping member and to itself move into locking engagement with the second named telescoping member against the tendency of 55 the spring actuated latch.

4. In a coke oven apparatus, a telescoping structure consisting of a number of members adapted to be projected into a coke oven, one member telescoping into the next larger 60 member, racks on the telescoping members, and a driving pinion for said racks, a fixed structure into which the telescoping members are movable, a spring actuated latch carried by the fixed member, a locking member carried by each of the telescoping mem- 65

bers, except the outermost one, said locking member first raising and releasing the latch and releasing the next outer member and also locking the said next outer member to itself, and a rock lever coming in contact 70 with the periphery of the driving pinion, thereby forcing the locking bolt to place, when the relatively inner telescoping member is at the limit of its projected position.

5. In a coke oven apparatus, telescoping members and means for coupling and uncoupling the telescoping members, comprising a spring actuated latch member in the path of a relatively outer telescoping member and arranged to project therethrough and 80 into the path of another telescoping member, and a lever actuated lock pin carried by the second telescoping member into engagement with the latch, said lock pin raising the latter out of engagement with the first named telescoping member when coincident therewith, and moving into locking engagement with the said first named telescoping member.

6. In a coke oven apparatus, telescoping members adapted to be projected into a coke oven, rack and pinion actuating means for the telescoping members, a latch member carried upon a fixed portion of the structure in operative relation to a relative outer one of the telescoping members, and a locking member carried by a relatively inner one of the telescoping members, said locking member comprising a longitudinally movable pin, and a lever connected to said pin and 95 movable into the path of the pinion engaging the rack moving the said telescoping member.

7. In a coke oven apparatus, telescoping members adapted to be projected into a coke oven, rack and pinion actuating means for the telescoping members, a latch member carried upon a fixed portion of the structure in operative relation to a relatively outer one of the telescoping members, and a locking member carried by a relatively inner one of the telescoping members, said locking member comprising a longitudinally movable pin, a lever connected to said pin and movable into the path of the pinion engaging the rack moving the said telescoping member, and a spring tending to move the lever in a direction to project the pin into engagement with the said other telescoping member.

8. In a coke oven apparatus a series of 120 telescoping members to move one within the other, means for actuating the telescoping members, a housing receiving said telescoping members, a latch attached to said housing arranged to hold said telescoping members in place, a locking device carried by each of the telescoping members composed of a rocking lever with a bolt at one end and a yielding means at the other end, said locking device being placed in the path of the driving 125 130

means for the telescoping members and so arranged as to force the bolt into locking position as it passes over said driving means and unlock the same by withdrawing the 5 bolt from the next outer section on its return.

In testimony that we claim the foregoing

as our own, we have hereto affixed our signatures in the presence of two witnesses.
